UNITED STATES PATENT OFFICE

GEORGE W. SCHAEFER, OF SOUTH BRAINTREE, MASSACHUSETTS, ASSIGNOR TO ADDRESSOGRAPH COMPANY, OF WILMINGTON, DELAWARE, A CORPORATION OF DELAWARE

PRINTING DEVICE

Original application filed October 1, 1925, Serial No. 59,825. Divided and this application filed May 28, 1928. Serial No. 281,302.

This application is a division of my application Serial No. 59,825, filed October 1, 1925.

This invention relates to printing devices which include a frame having a printing plate 5 with embossed characters detachably mounted on the frame and which are adapted to be stored in accordance with a card index system or in a stack and to be run through an addressing or other suitable machine for taking impressions from the form.

The object of the invention is to provide novel and simple means for detachably holding one or more printing plates on the frame.

And another object of the invention is to 15 provide a novel and simple retaining device struck up from the frame for detachably holding oppositely disposed printing plates on the frame.

In the accompanying drawings illustrating a selected embodiment of the invention:

Fig. 1 is a front elevation of a printing device.

Fig. 2 is a fragmentary portion of the printing device showing the invention on a 25 larger scale.

Figs. 3 and 4 are vertical sectional views on the lines 3-3 and 4-4 respectively of Fig. 2.

Fig. 5 is a horizontal sectional view on the line 5-5 of Fig. 2.

Referring to the drawings 6 is a metal frame, 7, 8 are printing plates having printing characters embossed thereon and 9 is a record card, the frame having suitable retaining devices for detachably holding the plates 30 and card thereon.

The invention comprises a stud or button 10 which may be circular or other suitable shape and made by cutting the frame and striking up the part between the cuts to lie 40 in a plane above the front of the body of the frame. The cuts 11, 11 are spaced apart and the stud is connected to the body of the frame by a neck 12 at its top and by a neck 13 at its bottom. This provides a retaining 45 stud integral with the body of the frame and lying in a plane above the front of the body of the frame to overlap the plates 7 and 8 which are arranged on opposite sides of the stud. The stud is located between the plates

50 7 and 8 and other suitable retaining means

are provided on the frame to cooperate with the stud for holding the plates on the frame. These other retaining devices may comprise a bead 14 at the bottom of the frame engaging the lower edges of the plates 7 and 8, a yielding stop 15 engaging a notch 16 at the outer end of plate 7 and a yielding stop 17 engaging a notch 18 at the outer end of plate 8. I may also provide a yielding stop 19 engaging a notch 20 at the inner end and a lip 21 engaging the outer end of plate 8. These yielding stops are more fully set forth in my original application Serial No. 59,825. The card 9 is detachably held on the frame by the bead 22 at the top edge of the frame and by stops 23 and lips 24. Any other suitable retaining means may be used in cooperation with the stud 10 for holding the plates on the frame and any other suitable retaining means may be employed for holding the card.

The stud forms a simple means struck up from the body of the frame for overlapping and holding one or more plates on the frame. It is conveniently located between two plates 75 as shown for retaining both plates on the frame.

I have shown my invention embodied in a frame similar to that disclosed in my original application and in a simple form which I have found satisfactory for the purpose, but I reserve the right to embody the invention in other frames and to make changes therein within the scope of the following claims:

I claim:

1. A printing device of the character described comprising a sheet metal frame, two printing members arranged on the frame in adjacent relation, and means integral with the frame intermediate the two printing members for detachably securing said members on the frame, said means comprising a stud struck up from the body of the frame between said members and having portions thereof arranged to engage opposed edges of the members.

2. A printing device of the character described comprising a sheet metal frame, two printing members arranged on the frame in adjacent relation, and means integral with

the frame intermediate the two printing members for detachably securing said members on the frame, said means comprising a stud struck up from the body of the frame 5 and having free side edges to overlap opposed edges of the members.

3. A printing device of the character described, comprising a sheet metal frame, two printing members arranged on the frame in 10 adjacent relation, and means integral with the frame for detachably securing said members on the frame, said means comprising a stud struck up from the body of the frame between opposed edges of the members and 15 having free edges to overlap said opposed edges and necks between said opposed edges connecting the stud with the body of the frame.

GEORGE W. SCHAEFER.
